GARMENT HANGER CARRIER

Charles H. Borten, Kyoto Bldg., Suite 1-U, Towers of
Windsor Park, Cherry Hill, N.J. 08034

Filed May 19, 1970, Ser. No. 23,055

Term of patent 14 years

Int. Cl. D8—07

U.S. Cl. D8—15 A

FIG. 1 is a front elevational view of a garment hanger carrier showing my new design, the rear being a mirror image of the front shown;

FIG. 2 is an elevational view taken from one end thereof;

FIG. 3 is an elevational view taken from the end opposite that shown in FIG. 2;

FIG. 4 is a top plan view thereof; and

FIG. 5 is a bottom plan view thereof.

I claim:

The ornamental design for a garment hanger carrier, as shown.
